UNITED STATES PATENT OFFICE

ELIHU D. WATT, OF PLAINFIELD, NEW JERSEY, ASSIGNOR TO RAYMOND CONCRETE PILE COMPANY, OF NEW YORK, N. Y., A CORPORATION OF NEW JERSEY

COMPOSITE PILE JOINT

Application filed September 20, 1932. Serial No. 633,966.

This invention pertains to composite piles in which the lower section is of wood, and the upper section is of concrete.

The primary object of the invention is to disclose an improved joint for interlocking the upper and lower sections to prevent their separation after driving.

In the present invention, a wedge ring is used as in Watt and Whiteley Patent No. 1,865,657, but the ring is here used and applied in a different manner.

Further and other objects and advantages will be apparent from the specification and claims, and from the accompanying drawing which illustrates what is now considered the preferred embodiment of the invention.

Fig. 1 shows the lower pile section with the drive head in position during the driving operation.

Fig. 2 shows the drive head, follower, wedge ring and other parts in position to resume driving after the shell for the upper section has been placed in position.

Fig. 3 shows the joint between the sections after the driving is completed and the upper section is filled with concrete.

In the drawing, 10 is the lower wooden pile section, and 12 is the drive head provided with downwardly projecting annular wedges 14 and 16, which, during the operation of driving the lower section, form annular grooves 18 and 20 in the flat top surface of that section (Fig. 2).

After section 10 has been driven until its upper end approaches ground level, as in Fig. 1, drive head 12 is removed, wedge ring 22 is placed with its lower edge in groove 18 (Fig. 2), shell 24 is placed with its upper end in groove 20, and follower 26 surmounted by drive head 12 is lowered into position as in Fig. 2, with its lower end resting on wedge ring 22, and on shoulder 28 provided at the lower end of the shell. This shoulder is usually formed in a ring 30 of metal thicker than the shell and welded thereto. The lower part 32 of the ring, below the shoulder, is usually conical and substantially parallel to the outer surface of wedge ring 22.

The upper end of follower 26 is provided with a head 34 having an annular recess 36

to freely accommodate rings 14 and 16 of drive head 12.

With the parts arranged as above described, and as shown in Fig. 2, driving is resumed. The first blow on follower 26 forces wedge ring 22 into its groove 18, and cone 32 into its groove 20. The ring of wood 32 is forced radially outwards by wedge ring 22 to become locked between the conical surfaces of cone 32 and ring 22, thus securely locking the shell of the upper section to the upper end of the lower section.

After the wedge ring and cone 32 have been driven home, further driving of follower 26 forces lower section 10 into the ground with shell 24 following down into the hole formed by the lower section. After the proper depth is reached, the follower is withdrawn and the shell is filled with concrete 40 to form the complete composite pile, as indicated in Fig. 3.

It is to be understood that the invention is not limited to the specific embodiment herein illustrated and described, but may be used in other ways without departure from its spirit as defined by the following claims:

I claim:

1. In the method of forming a composite pile having a lower section of wood and a shell surmounting said lower section, said shell having a lower end of restricted diameter, the steps of mounting said shell on said lower section whereby said restricted portion enters an annular groove in the flat top of said lower section, flaring out a portion of said lower section into engagement with said restricted portion, and then filling the shell with concrete.

2. In the method of forming a composite pile having a flat-topped lower section and a shell surmounting said section, the steps of mounting said shell on top of said lower section, causing said shell to enter the flat upper end of said lower section, and filling the said shell with concrete.

3. In the method of forming a composite pile having a lower section of wood and a shell surmounting said lower section, said shell having a lower end of restricted diameter, the steps of mounting said shell on

said lower section whereby said restricted portion enters an annular groove in the flat top of said lower section, flaring out a portion of said lower section into engagement with 5 said restricted portion during the driving of the lower section, and then filling the shell with concrete.

4. In the method of forming a composite pile having a flat-topped lower section and a 10 shell surmounting said section, the steps of mounting said shell on top of said lower section, causing said shell to enter and fill a groove in the upper end of said lower section during the driving of the lower section, and 15 filling the said shell with concrete.

5. In a composite pile, a flat-topped lower section of wood, a shell surmounting said lower section and adapted for receiving concrete to form the upper pile section, and 20 means for locking the lower end of said shell into the flat top of said lower section.

6. In a composite pile, a flat-topped lower section of wood, a shell surmounting said lower section and adapted for receiving concrete to form the upper pile section, and 25 means comprising a wedge ring for causing the top of said lower section to engage the lower end of said shell for locking the lower end of said shell into the flat top of said 30 lower section.

7. In a composite pile, a flat-topped lower section of wood, a shell surmounting said lower section and adapted for receiving concrete to form the upper pile section, said shell 35 having a lower end of reduced diameter, and a wedge ring adapted to cooperate with said reduced lower end for locking the lower end of said shell into the flat top of said lower pile section.

40 8. A composite pile comprising, in combination, a flat-topped lower section of wood, and an upper section of concrete, said upper section being encased by a shell, and means

45

for locking the lower end of said shell into the flat-top of said lower section.

9. A composite pile comprising, in combination, a flat-topped lower section of wood, and an upper section of concrete, said upper 70 section being encased by a shell, and means comprising a wedge ring for locking the lower end of said shell into the flat-top of said lower section.

10. The method of forming a composite 75 pile having a flat top lower section of wood and a shell surmounting said lower section, said shell having a lower end of restricted diameter, the steps of driving said lower section into the ground and simultaneously 80 forming grooves in the flat top of said lower section, mounting the shell on said lower section and further driving said lower section to draw down the shell into the hole formed by the lower section and simultaneously 85 driving the restricted lower end of the shell into one of the grooves and flaring out a portion of said lower section into engagement with said restricted portion.

11. The method of forming a composite pile 90 having a flat top lower section of wood and a shell surmounting said lower section, said shell having a lower end of restricted diameter, the steps of driving said lower section into the ground and simultaneously 95 forming grooves in the flat top of said lower section, mounting the shell on said lower section and further driving said lower section to draw down the shell into the hole formed by the lower section and simultaneously driv- 100 ing the restricted lower end of the shell into one of the grooves and flaring out a portion of said lower section into engagement with said restricted portion and then filling the shell with concrete.

105 In testimony whereof I hereto affix my signature.

ELIHU D. WATT.
